United States Patent Office

Des. 181,736
Patented Dec. 17, 1957

181,736

TRUCK BODY

Fred A. Lee, Fort Wayne, Ind., assignor to International Harvester Company, Chicago, Ill., a corporation of
New Jersey

Application May 1, 1957, Serial No. 45,968

Term of patent 7 years

(Cl. D14—3)

Figure 2 is a rear perspective view taken with the body portion in an open position.

The portions shown in broken lines are for illustrative purposes only.

I claim:

The ornamental design for a truck body, substantially as shown and described.
